MULTIPLE STOCK QUOTATION PRO-
JECTING MACHINE

August D. Eitzen, Rockville Centre, N. Y., assignor
to News Projection Corporation, New York,
N. Y., a corporation of New York

Application April 10, 1929, Serial No. 354,035
Renewed November 16, 1933

13 Claims. (Cl. 88--24)

My present invention relates generally to stock quotation devices, and has particular reference to a stock quotation projecting machine.

It is customary practice at the present time to 5 associate a stock ticker which is adapted to discharge marked tape in a substantially continuous manner with a projecting device through which the tape is made to pass and by means of which the markings on the tape are displayed 10 upon a relatively large screen which commands a substantial observation area. After the tape leaves the projecting device it is guided toward a take-up or rewinding mechanism of suitable character.

15 It is frequently desirable to render the markings on the tape readable from different observation areas. For example, in many brokerage offices, a separate room is assigned to ladies, and a separate display screen in each room is therefore desirable. Similarly, it is often advantageous to have a main display screen in a public room and a second display screen in a private room.

20 Before pointing out the features of my present invention, I will premise that the projection of images onto two separated screens is a matter of considerable expense where a separate ticker and projecting device are provided for cooperation with each screen. On the other hand, if this 25 expense were to be minimized by employing a single ticker and a pair of projecting devices through which the tape would successively pass, then the markings projected by the second projecting device would be objectionably late in time so far 30 as the actual stock transactions indicated by such markings are concerned.

35 It is a general object of my present invention to provide a stock quotation projecting machine which may be efficiently and satisfactorily employed for the creation of images of tape markings on two independent and separated screens, without necessitating any of the expense involved in duplication of expensive parts.

40 Another object is to provide a machine of this character which will serve to create images on at least two screens with the same promptness as the same would have been produced upon a single screen in accordance with customary practice.

45 More particularly, it is an object of my invention to provide a projecting machine for use with a pair of divergently directed display screens, the machine comprising a common ticker, a common 50 projecting device, and means for creating the de-

sired images in a prompt and efficient manner on both screens.

Briefly, I accomplish this general object by 5 creating a main beam of light which emanates from the projecting device after having passed through the tape, and by thereupon directing said beam partially toward one screen and partially toward the other screen. In a co-pending application I have illustrated and described one manner of accomplishing this object by splitting 10 the main beam into two subordinate beams and thereupon directing such subordinate beams toward and onto the two display screens respectively.

15 Where a beam of light is split into two subordinate portions, the intensity of each of the latter is less than that of the original beam. In accordance with my present invention I create a pair of subordinate beams each of which has the same intensity as the initial beam. Briefly, 20 I accomplish this advantageous result by deflecting the entire beam at rapid intervals so that each of the subordinate beams produced is a pulsating beam. The alternations are of sufficient rapidity to render the images produced by 25 each beam upon one of the screens readable in a satisfactory manner.

30 In a co-pending application I have accomplished the production of two subordinate pulsating beams of the foregoing character by means 35 of one or more reflectors arranged in a common plane and movable across the path of the original beam in a plane coincident with such reflectors. In the form herein illustrated and described, the features of which are hereinafter set 40 forth in the appended claims, I again employ the interposition and withdrawal of a reflector or reflectors into and from the path of the original beam of light, but instead of moving such reflector or reflectors in a plane coincident with them- 45 selves, I move them transversely of such plane. A construction of this character has numerous advantages, as will be more fully understood after this specification has been read.

More particularly, I provide a pivoted member 45 provided with at least one reflecting surface, and in conjunction with such surface I provide either a transparent portion or a second reflecting surface set at an angle to the first. I also provide means for pivoting said member to and fro so as 50 to interpose one or both reflecting surfaces into the path of the original beam of light in the proper manner for achieving the desired purpose.

55 A particular feature of my present invention

resides in providing a shutter which is movable across the path of light to permit the passage of the beam therethrough or to block such passage entirely at predetermined times. More particularly, I provide means for so operating the shutter that during movements of the reflecting surface or surfaces the shutter is automatically positioned to block the beam of light, whereas during periods of rest of the reflector or reflectors, the shutter is automatically opened to permit the beam of light to be directed in the contemplated manner.

Other features of my present invention reside in the particular manner of oscillating or pivoting the member referred to and also automatically operating the shutter as aforesaid. It is a general feature of my present invention to provide a construction which is simple in structural nature and inexpensive from a manufacturing standpoint.

For the attainment of the foregoing objects and such other objects as may hereinafter appear or be pointed out, I have illustrated two forms of my invention in the accompanying drawing 25 wherein—

Figure 1 is an elevational view of a projecting device constructed in accordance with my present invention and showing diagrammatically the manner in which images are simultaneously produced on a pair of separated screens, certain portions of the mechanism being omitted from this figure for the sake of clearness;

Figure 2 is a view taken from the right of Figure 1 and substantially along the line 2—2 thereof, showing certain details of the mechanism which were omitted in Figure 1;

Figure 3 is a plan view taken substantially along the line 3—3 of Figure 1 and illustrating the arrangement of certain reflecting surfaces, certain portions being omitted from this figure also for the sake of clearness;

Figure 4 is a view taken from the left of Figure 2, as indicated at 4—4 in Figure 2, and showing on an enlarged scale certain details of the mechanism;

Figure 5 is a view similar to Figure 4 showing the parts in different relative positions; and

Figure 6 is a view similar to Figure 1 illustrating a modification.

Referring to the drawing, and particularly to Figure 2, I have diagrammatically illustrated a stock ticker 10 from which a marked tape 11 is adapted to be discharged. This tape has been shown entering and passing through a projecting device 12, after which it is led toward a suitable take-up or rewinding mechanism designated by the reference numeral 13.

The foregoing elements are designed to cooperate with a pair of screens 14 and 15. It is to be noted that these screens are spaced from each other, and I have illustratively shown them facing in divergent directions, thereby serving two different observation areas. The screen 15 may typify a screen which would command an observation area in, for example, one room, and the screen 14 may be said to represent a second screen arranged within an adjoining room.

In accordance with my invention, a suitable source of light (not shown) is arranged within the projecting device 12 and is adapted to project a beam 16 upwardly through the tape 11 as the latter passes through the device 12. I prefer to arrange an objective 17 in the path of this beam. In the illustrated embodiment, I have shown a shutter arranged directly above the ob-

jective 17, which shutter may take the form of a cylindrical sleeve 18 mounted for rotation upon a spindle 19 passing through the axis of the cylinder. The element 18 is provided with the diametrically opposite apertures 20 which are of sufficient size to permit the beam leaving the objective 17 to pass upwardly therethrough when they are in vertical alignment. Similarly, these apertures are so sized and positioned that when the sleeve 18 is rotated through 90°, the passage of 10 the beam through the shutter is entirely blocked.

In the embodiment illustrated in Figures 1-5, I have provided above the shutter 18 a member 21 pivoted at 22 for oscillation between the two extreme positions illustrated in Figures 4 and 5. 15 This member is provided with two reflecting surfaces 23 and 24 arranged at an angle to each other. The angular mounting of these surfaces is such that when the member 21 is in one extreme position as shown in Figure 4, then the beam 16 20 passing upwardly through the shutter 18 is adapted to encounter the reflecting surface 24 and be deflected in a lateral direction to provide one subordinate beam 25; whereas a positioning of the member 21 in its opposite extreme position 25 as shown in Figure 5 will cause the upwardly passing beam 16 to encounter the reflecting surface 23 for deflection by the latter into the opposite lateral direction to produce the second subordinate beam 26.

Before describing further details of the mechanism, it will be obvious that a rapid oscillation of the member 21 between its two extreme positions, accompanied by a predetermined period of rest in each extreme position, will result in the 35 production of two subordinate beams, one of which follows the direction 25 of Figure 4 and the other of which extends in the direction 26 of Figure 5, each of these subordinate beams being of a rapidly pulsating character.

For accomplishing such rapid oscillation I prefer to provide mechanism of the character illustrated most clearly in Figures 2, 4, and 5. I have shown a cam disc 27 mounted upon the end of the spindle 19, a motor or the like 28 serving constantly to rotate the spindle 19 and the disc 27. The speed of the motor 28 may be regulated by means of a rheostat 29 or the like.

In the outer surface of the disc 27 I provide a suitably contoured cam groove 30 adapted to 50 receive a cam follower roller 31 therein. The roller 31 is mounted on the end of a cam follower arm 32 associated with the member 21 and preferably with the axis 22 of the latter.

Upon referring to Figures 4 and 5 it will be observed that rotation of the disc 27 in the direction of the arrow 33 will cause the arm 32 to swing between the positions illustrated, resting for a predetermined time in each extreme position, this oscillation of the arm 32 causing a similar oscillation of the spindle 22 and the pivoted member 21.

For the purpose of automatically blocking the beam of light 16 during movements of the member 21 and of its associated reflecting surfaces 23 and 24, I cause the motor 28 to serve the additional function of rotating the shutter 18. By suitably mounting this shutter upon the spindle 19, particularly with respect to its angular relationship with the disc 27, I am enabled to provide 70 for the automatic contemplated operation by the mere constant rotation at uniform speed of the spindle 19. Thus, in Figure 4, the arm 32 has just commenced its period of rest at one extreme position, and for a predetermined period of time 75

the aperture 20 will permit the beam of light 16 to encounter the momentarily stationary mirror 24. Presently, the shutter 18 will cause a blocking of the beam 16 after which the arm 32 will be rapidly swung into the position of Figure 5. In this position, the apertures 20 will again be aligned for a predetermined period to allow the beam 16 to encounter the momentarily stationary reflector 23.

In Figures 1, 2, and 3 I have illustrated the manner in which the two subordinate beams are directed toward and onto their respective screens. The pulsating subordinate beam 26 is caused first to encounter a mirror or reflector 34 set at an angle of substantially 45°. From here, the beam is reflected onto the reflecting member 35 arranged at approximately 45° to the horizontal. The beam is in this way deflected upwardly onto the reflector 36 which serves in turn to project the markings onto the rear of the screen 14. The provision of an even number of mirrors results in the production of an erect and un-inverted image upon the forward face of the screen 14. The latter will be obviously of the well-known translucent variety which will render the readings visible on the front face thereof.

With respect to the subordinate beam 25, a reflector 37 is positioned to deflect this beam upwardly onto the mirror 38, thence toward the mirror 39, and finally onto the rear of the screen 15 of construction similar to the screen 14.

In the embodiment illustrated in Figure 6, the reflecting surface 24 has been omitted from the pivoted member. In this case, a member 40 corresponding to the member 21, is pivoted at 41 and is provided with the single reflecting surface 42. The latter corresponds to the reflecting surface 23 previously referred to. In place of the second reflecting surface, an aperture or trans-parent portion is provided whereby the beam is directed at once onto the reflector 38. The omission of the mirror 24 is accompanied by an omission of the reflector 37, whereby the erect and un-inverted nature of the image is unaffected. The surface 42 serves to produce a subordinate beam 26 in the same manner as hereinbefore described.

It will thus be seen that I have provided a construction which is extremely simple, yet highly satisfactory. Although I have illustrated two screens facing in different directions, it will be understood that a suitable arrangement of reflecting surfaces may enable various other dis-positions of two screens. The provision of a pivoted member carrying reflecting surfaces and operating in the manner described enables the two subordinate beams to be directed into the desired proper directions. In certain cases, more than two subordinate beams may thus be created.

It will also be understood that the particular means for oscillating and moving the various elements may be varied to suit differing requirements. The construction illustrated has numer-ous advantages and is therefore preferred.

In general, it will be obvious that changes in the details herein described and illustrated for the purpose of explaining the nature of my in-vention may be made by those skilled in the art without departing from the spirit and scope of the invention as expressed in the appended claims. It is therefore intended that these de-tails be interpreted as illustrative, and not in a limiting sense.

Having thus described my invention and illus-trated its use, what I claim as new and desire to secure by Letters Patent is—

1. In a stock quotation projecting machine having a ticker adapted to mark and discharge tape with reading matter readable longitudinally of the tape, the combination with a pair of screens, of a projecting device through which the marked tape passes, said device comprising a source of light arranged to project a beam through the tape, means for alternately direct-ing said beam toward said screens, and a shutter for blocking said beam entirely between the alter-nations to prevent the projection of distor-tions during projection interruption.

2. In a stock quotation projecting machine having a ticker adapted to mark and discharge tape with reading matter readable longitudinally of the tape, the combination with a pair of screens, of a projecting device through which the marked tape passes, said device comprising a source of light arranged to project a beam through the tape, and means for alternately directing said beam toward said screens; said means including a movable reflector, means for intermittently interposing and withdrawing said reflector into and from the path of said beam, and a shutter for blocking said beam entirely during movements of the reflector to prevent the projection of distortions during projection in-terruption.

3. In a stock quotation projecting machine having a ticker adapted to mark and discharge tape with reading matter readable longitudinally of the tape, the combination with a pair of screens, of a projecting device through which the marked tape passes, said device comprising a source of light arranged to project a beam through the tape, and means for alternately di-recting said beam toward said screens; said means comprising a movable reflector having angularly disposed reflecting surfaces, and means for intermittently moving the reflector to 40 interpose said surfaces alternately into the path of said beam.

4. In a stock quotation projecting machine having a ticker adapted to mark and discharge tape with reading matter readable longitudinally of the tape, the combination with a pair of screens, of a projecting device through which the marked tape passes, said device comprising a source of light arranged to project a beam through the tape, and means for alternately di-recting said beam toward said screens; said means comprising a movable reflector having angularly disposed reflecting surfaces, and means for inter-mittently oscillating the reflector to interpose said surfaces alternately into the path of said beam.

5. In a stock quotation projecting machine having a ticker adapted to mark and discharge tape with reading matter readable longitudinally of the tape, the combination with a pair of screens, of a projecting device through which the marked tape passes, said device comprising a source of light arranged to project a beam through the tape, and means for alternately di-recting said beam toward said screens; said means comprising a movable reflector having angularly disposed reflecting surfaces, means for moving the reflector to interpose said surfaces alternate-ly into the path of said beam, and a shutter for blocking said beam entirely during movements of the reflector to prevent the projection of distor-tions during projection interruption.

6. In a stock quotation projecting machine having a ticker adapted to mark and discharge tape with reading matter readable longitudinally of the tape, the combination with a pair of

- screens, of a projecting device through which the marked tape passes, said device comprising a source of light arranged to project a beam through the tape, and means for alternately 5 directing said beam toward said screens; said means comprising an oscillatable member provided with angularly arranged reflecting surfaces, means for oscillating said member to interpose said surfaces alternately into the path 10 of said beam, and a shutter for blocking said beam entirely during oscillations of said member to prevent the projection of distortions during projection interruption.
7. In a stock quotation projecting machine 15 having a ticker adapted to mark and discharge tape with reading matter readable longitudinally of the tape, the combination with a pair of screens, of a projecting device through which the marked tape passes, said device comprising a 20 source of light arranged to project a beam through the tape, and means for alternately directing said beam toward said screens; said means comprising an oscillatable member provided with angularly arranged reflecting surfaces, a movable 25 shutter, and means for oscillating said member and moving said shutter in timed relationship so as to interpose said surfaces alternately into the path of said beam and to block said beam entirely during oscillations of said member 30 to prevent the projection of distortions during projection interruption.
3. In a stock quotation projecting machine having a ticker adapted to mark and discharge tape with reading matter readable longitudinally of the tape, the combination with a pair of screens, of a projecting device through which the marked tape passes, said device comprising a 35 source of light arranged to project a beam through the tape, and means for alternately directing said beam toward said screens; said means including an oscillating reflector, and means for intermittently rocking said reflector to and fro for intermittently interposing it into the path of said beam.
- 45 9. In a stock quotation projecting machine having a ticker adapted to mark and discharge tape having reading matter readable longitudinally of the tape, the combination with a pair of spaced screens, of a common projecting device 40 through which the marked tape passes, said device including a source of light arranged to project a beam through said tape, means for alternately deflecting the entire beam at rapid intervals into opposite directions to produce two 50 pulsating subordinate beams, and reflecting

means for intermittently directing said subordinate beams toward and onto said screens respectively to produce an erect and uninverted image of said markings on each of said screens simultaneously.

10. In a stock quotation projecting machine, the combination with a ticker adapted to discharge marked tape, of a pair of screens, and a projecting device through which the marked tape passes, said device comprising a source of light 10 arranged to project a beam through the tape, and means for alternately directing said beam toward said screens; said means including a pivoted reflector, a cam follower carried thereby, a cam, and a motor for rotating said cam to pivot said 15 reflector so as to interpose the latter intermittently into the path of said beam.

11. In a stock quotation projecting machine, the combination with a ticker adapted to discharge marked tape, of a pair of screens, and a 20 projecting device through which the marked tape passes, said device comprising a source of light arranged to project a beam through the tape, and means for alternately directing said beam toward said screens; said means including a 25 pivoted reflector, a cam follower carried thereby, a shutter, a cam carried by the latter, and means for simultaneously operating said shutter and cam so as to rock said reflector intermittently into the path of said beam and to block said beam 30 entirely during movements of the reflector.

12. In a stock quotation projecting machine having a ticker adapted to mark and discharge tape with reading matter readable longitudinally of said tape, and having a projecting device 35 through which the marked tape passes, said device comprising a source of light cooperating with said tape to produce a beam of light carrying traveling images of said reading matter, the combination of means for directing said beam alternately toward the pair of spaced screens, and a shutter for blocking said beam entirely between the alternations, to prevent the projection of distortions during projection interruption.

13. The combination with a pair of screens, of a projecting device through which marked tape passes, said device comprising a common source of light arranged to project a beam through the tape, means for alternately directing said beam toward said screens, a shutter for blocking said beam between alternations, and means for arresting said directing means during projection to prevent the projection of distortions.
